UNITED STATES PATENT OFFICE.

SYVER LOE, OF MINNEAPOLIS, MINNESOTA, ASSIGNOR, BY DIRECT AND MESNE ASSIGNMENTS, TO LOE MULTIPLEX VOTING MACHINE COMPANY, OF MINNEAPOLIS, MINNESOTA, A CORPORATION OF MINNESOTA.

PRIMARY-ELECTION MECHANISM FOR VOTING-MACHINES.

1,305,134.

Specification of Letters Patent. Patented May 27, 1919.

Application filed May 24, 1917. Serial No. 170,724.

To all whom it may concern:

Be it known that I, SYVER LOE, a citizen of the United States, residing at Minneapolis, in the county of Hennepin and State 5 of Minnesota, have invented certain new and useful Improvements in Primary-Election Mechanism for Voting-Machines; and I do hereby declare the following to be a full, clear, and exact description of the 10 invention, such as will enable others skilled in the art to which it appertains to make and use the same.

My invention has for its object to provide a novel primary election mechanism for voting machines, and to such ends generally stated, the invention consists of the novel devices and combinations of devices herein-after described and defined in the claims.

The principal object of my present invention is to provide a machine adapted 20 for use at primary elections, which, in many districts and in some States, are required to be carried out on the so-called "Australian system" of voting. More specifically stated, 25 at these primary elections, the candidates for the various offices must be determined beforehand by certain rules, not necessary here to consider, and they must be represented on a prepared ticket and the voter 30 must cast his vote within a booth or in private. The chief difference in the manner of voting at a primary election and at a final election is that the voter in the former instance must select his political party and 35 must then vote only for candidates for nomination belonging to that party, while at a final election the so-called "split ticket" may be voted.

My invention provides a simple and efficient mechanism for accomplishing the 40 above result.

In the accompanying drawings which illustrate the invention, like characters indicate like parts throughout the several 45 views.

Referring to the drawings,

Figure 1 is a view in front elevation with some parts broken away, showing a voting machine embodying my invention. This 50 voting machine may be assumed to be of the type disclosed and claimed in my compan-

ion application filed of even date herewith and entitled "Voting machine";

Fig. 2 is a fragmentary view in front elevation with some parts sectioned and some parts broken away, showing the lower portion 55 of the keyboard and coöperating mechanism;

Fig. 3 is a plan showing a section of the upper portion of the keyboard and frame, 60 some parts being broken away and some parts being removed;

Fig. 4 is a section taken on the line 4—4 of Fig. 2;

Fig. 5 is a rear or inside elevation of the 65 parts shown in the vicinity of the line marked 5—5 of Fig. 4;

Fig. 5^a is a detail in elevation of a coupling link;

Fig. 6 is a section taken on the line 6—6 70 of Figs. 4 and 5;

Fig. 7 is a section on the line 7—7 of Fig. 4;

Fig. 8 is an elevation looking at the inner 75 side of a cover strap and lock mechanism shown in Figs. 4, 6 and 7;

Fig. 9 is a plan view of the parts shown in Fig. 8; and

Fig. 10 is a section on the line 10—10 of Fig. 2. 80

In Figs. 8 and 9, the cover plate is shown as straightened out, but when applied to the machine, as shown in the views noted, it will follow the curve on the outer portion of the lower frame section of the keyboard 85 mechanism.

In the machine illustrated, the keyboard framework is made up of a multiplicity of interlocking blocks, an upper frame and a lower frame. The said interlocking blocks 90 which are indicated as entireties by the numeral 10, may be, and preferably are of the character disclosed and claimed in my companion application filed of even date herewith and entitled "Keyboard mechanism." 95 The said lower frame, as shown, is a curved or segmental structure made up of vertically spaced horizontal plates 11 and upright connecting brackets 12. The upper frame of the keyboard mechanism, likewise, 100 is made up of vertically spaced horizontal plates 13 and upright connecting brackets

14. The register actuators are also preferably of the character disclosed and claimed in my said companion application entitled "Keyboard mechanism" and they are combined with expansible vote limiting devices, preferably of the character disclosed in the said application.

When the machine is adjusted for use at general elections where mixed tickets can be voted, all of the actuators of the several columns or vertical groups must be released so that the voter may manipulate any thereof, subject only to the limitations imposed by the properly adjusted vote limiting devices. The actuators assigned to any particular office will be in the same vertical column, or, if in two columns, the two columns must be connected to operate the one as a continuation of the other. For example, in considering the three vertical rows of register actuators shown in Fig. 2, the row at the left may be assumed to be used for nonpartisan candidates, or to the voting of questions, such as constitutional amendments, and the like; the row at the center may be assumed to be used for the Republican party; and the row at the right for the Democratic party.

Each register actuator (see particularly Fig. 10) is made up of a finger-actuated lever 15, a register actuating lever 16, an adjusting collar 17, and a hub 18.

The expansible vote limiting device comprising externally-threaded hubs 19 and internally threaded sleeve members 20. The hubs 18 are fitted to slide vertically on angular shafts 21 mounted in the two lower frame plates 11 and in the lower of the upper frame plates 13. The upper and lower ends of these shafts 21 are made round and spur pinions 22 are secured to the rounded upper ends of said shafts (see Figs. 1 and 7).

Each lever 16 has a slotted arm in which works a cam pin 23 carried by a projecting arm of the coöperating lever 15. Each lever 15 has a lock lug 24 and each hub 18 has a projecting lock lug 25 that is arranged to engage with a depending lug 26 carried by each coöperating overlying lever 15. The adjusting collars 17 may be assumed to be fixed to the levers 16, and they have interlocking engagement for common rotation with the coöperating internally-threaded sleeve members 20, but the latter may move vertically in respect to the former and in respect to the said members 16.

For each vertical stack of levers 15, there is a notched lock bar 27. These lock bars 27 are mounted to slide vertically through suitable guideways 28 formed in the assembled blocks 10. Each lock bar 27 has a lug 27^a one for each lever, and in the normal positions of said bars, the said lugs are aligned with the lugs 24 of the respective levers 15, and so as to thereby lock the said levers 15, and

hence, the register actuators, in their normal or inoperative positions. The normal position of the register actuator is shown at the left in Fig. 10, and the set or operative position thereof is indicated at the right in Fig. 10.

The lower end of each lock bar 27 is connected by a link 29 to an oscillatory head or tumbler 30 which has a weighted or heavy side 30^a. This head 30 is secured on a short shaft 31 journaled in the lower brackets 12 and in its outer end having a recessed angular seat 31^a with which a key or wrench may be engaged to oscillate the same. Each oscillating head 30 is provided with a cam lug 30^b that is engaged by a cam wheel 32 loosely mounted on the rounded lower end 21 of the corresponding re-setting shaft 21. These cam wheels 32, each, have four large ratchet teeth in cylindrical arrangement for action on the said lugs 30^b.

Each cam wheel 32 carries a spring arm 33 which has a bell-shaped nose engaged with one or the other of the four V-shaped notches of the collar 34 rigidly secured to the corresponding shaft 21. Secured to each shaft 21 is a radial arm 35 (see Figs. 2, 4 and 7) which has a vertical pin 36 that operates as a dog on the coöperating ratchet wheel 32.

On the inner end of each shaft 31 is a head 37 having a lock tooth 37^a and a diametrically opposite flange with perforation 37^b and pin 37^c.

The so-called lock tooth of each head 37 is engageable with a coöperating notch 38 formed in a curved lock bar 39 that is slideable in suitable guides on the lower plate 11. At one end, the lock bar 39 has a beveled cam notch 40 and a rectangular lock notch 41. For coöperation with the notches 40 and 41, I provide a vertically movable lock bolt 42 (see Figs. 4 and 7). This lock bolt 42, at its upper and lower ends, has guide pins working through plates 11 and upper and lower bearing blocks 43, and it has a laterally projecting lock pin 44 for coöperation with the notches 40 and 41 of bar 39. The lock bolt 42 has a laterally projecting bracket 45 and is downwardly spring-pressed by a coiled spring 46 compressed between said bracket and upper plate 11. The arm 35 of one of the end or outside shafts 21 has a projecting cam pin 47 that is engageable with the bracket 45 to raise the lock bolt 42.

The pinions 22 on the upper ends of the several shafts 21 mesh with toothed sections of a curved rack bar 48 mounted to slide on the top plate 13 (see Figs. 3 and 7).

The numeral 49 indicates the voter's operating crank which is attached to the outer end of a shaft 50 mounted in suitable bearings on the upper bearing plate 13 and provided at its inner end with a spur gear 51, and at its intermediate portion, with a spiral

cam 52. This spiral cam 52 works between the prongs of a forked head 53 carried by a short upright rock shaft 54 mounted in a suitable bearing on the plate 13. At its 5 lower end, the shaft 54 has an arm 55 pivotally seated in a bearing 56 on the rack bar 48.

Normally, access to the key-holes 31^a is 10 cut off by a so-called cut-off bar 57 mounted to slide in suitable keepers on a shell plate 58 (see Figs. 6, 8 and 9) rigidly secured to the outer edges of plates 11. The plate 58 has perforations 59 that align with the key-holes 31^a and the cut-off plate 57 has perforations 60 adapted to be moved into and out 15 of registration with said perforations 59, but normally out of registration therewith, so that access cannot be had to the key-holes 31^a from the exterior of the machine. The 20 cut-off strip 57 is normally locked in its closed position shown in Figs. 8 and 9, by a key-actuated lock device. This lock device preferably comprises a Yale lock, the case 61 of which is secured to plate 58 and a rotary or tumbler member which has a crank 62 connected by a link 63 to the cut-off strip 57.

Operation.

As a preliminary in the preparation of the voting machine for use at a primary election, or for that matter, for use at any election, the cut-off strip 57, by manipulation 30 of the tumbler crank 62 of the lock 61, 35 is moved from the full line position, Fig. 8, into a position in which the key passages 60 will register with the key holes 31^a. This will set the cut-off strip so that the judge or attendant, by a suitable key, may manipulate 40 the shafts 31, and thereby, at will, move any one of the tumblers 30 from its normal position shown at the right in Fig. 2 into the position shown at the intermediate column Fig. 2. It will be noted that in the normal 45 position of the tumbler 30, the corresponding lock bar 27 is in a position to lock all of the register actuators of the vertical roll or column, as shown at the right in Fig. 2. It is equally evident that when the said tumbler 50 30 is moved into the position shown in the central group, Fig. 2, the said lock bar 27 is then set in a position to release all of the actuators of that group or corresponding vertical column of actuators. 55 Some columns will be assigned for non-partisan votes, such, for example, as constitutional amendments or for candidates representing no particular party but rather as candidates for all of the parties. For 60 such office, one of the columns of register actuators must be assigned, and we will assume that the left hand column, Fig. 2, is assigned for that purpose. The lock bar 27 of this column is dropped down to a position 65 below normal, so that it will release all of

the coöperating actuators, as shown, at the extreme left in Fig. 2. To set the left hand tumbler 30 in the position shown at the left in Fig. 2, and at the right in Fig. 5 (said Fig. 5 being a side view), a spring-pressed 70 lock pin 64 is engaged with the perforations 37^b of the said left hand head 37. The said lock pin 64 is mounted in one of the upright plates 12 and is subject to a leaf spring 65 (see particularly Figs. 5 and 6). 75

In the use of the machine at primary elections, the voter may announce the party for whom he intends to cast his vote. Assume, for example, that the voter announces himself as Republican. In this case, the judge 80 or attendant will turn the intermediate tumbler 30 from its normal position into the position shown in the central column, Fig. 2, thereby unlocking the actuators assigned to the central column and which is assumed to be assigned to the Republican candidates. The above noted movement of the tumbler 30 moves the corresponding shaft 31 and its head 37, thereby causing the lug 37^a of said head to enter the coöperating notch 38 of lock bar 39 and impart to the said lock bar a movement from the position indicated by full lines into the position indicated by dotted lines in Fig. 5. This movement of the lock bar 39 carries the unbroken upper surface of the said lock bar under all of the lugs 37^a of the heads 37 which remain in normal position, or, in other words, which remain not moved at the time that the first selector rocker 30 was moved. Hence, as is 95 evident, the operation of the first tumbler 30 will lock all of the other tumblers against movement with their coöperating lock bars 27 in their normal actuator locking positions. Thus by the very act of selecting and 100 unlocking actuators for one of the political parties, it is made impossible to release or actuate the register actuators of any other political party represented on the ticket. Hence, it, of course, follows that the key for 105 operating tumbler 30 and shaft 31 may be given to the voter and the voter allowed to make his own selection of party without announcing the same to the judge. 110

When lock bar 39 is moved by the first 115 operated tumbler 30, as just described, it will be moved from left to right, in respect to Fig. 5, or from right to left, in respect to Fig. 2, and the bevel notch 40 will cam itself out of engagement with pin 44 of lock bolt 42, and said lock pin 42 will then become automatically engaged with rectangular notch 41 of said bar 39, thereby positively locking said bar 39, against sliding movements in either direction. 120

After the voter has set the registers representing his entire vote and desires to cast the vote, he will signal the judge, who releases a certain lock, not necessary here to consider, but more fully disclosed and 130

claimed in my companion application entitled "Voting machine," and then the voter effects the casting of his vote by moving the voter's operating crank 49 from its position indicated by full lines in Figs. 1 and 3 into the position indicated by dotted lines in Fig. 1. Under this movement of said crank, a good many different actions take place, among which is the re-setting of the register 10 actuators to normal position, as more fully disclosed and claimed in my companion application entitled, "Keyboard mechanism."

Movement of the voter's crank 49 from normal position to dotted line position, is 15 limited by a fixed stop 49^a on the machine case. Movement of said crank in the first instance, from the upper side of said stop 49^a to the underside of said stop, causes cam 52, operating on bifurcated head 53, to rock 20 shaft 54 and its arm 55, thereby imparting an endwise movement to curved rack 48, in a direction from left toward the right, in respect to Fig. 3. This movement of said rack 48 operates pinions 22 of the several 25 setting shafts 21. Under this movement, lugs 25 of hubs 18 engage lugs 26 of levers 15 and restore set actuators to normal positions, and moreover, the first part of the above noted movement of the rack bar 48 30 causes cam pin 47 of arm 35 to engage cam bracket 45 of lock bolt 42 and thereby lift the pin 44 of the latter so as to release the sliding lock bar 39. This pin 47 maintains engagement with bracket 45 and holds lock bolt 42 raised for a considerable period of 35 time, during which period of time, the central ratchet-acting cam wheel 32, moving in the direction to carry the oblique surfaces of its teeth forward, (see Fig. 2), raises nose 40 30^b of the tumbler 30, and thereby rocks said tumbler into its normal position, which normal position is shown at the right in Fig. 2. This movement of the central tumbler 30 45 back to normal position, as just stated, takes place while lock 42 is released and it performs two functions, to wit, it moves lock bar 27 back to its normal actuator locking position and it causes lug 37^a to restore lock bar 39 to its normal position, in which position, the said lock bar will then be again 50 locked by engagement of lock pin 44 of bolt 42 with notch 40 of said lock bar 39.

When voter's lever 49 is moved back to normal position, rack bar 48 will be given 55 reverse movement and shafts 21 will be given reverse oscillation, thereby carrying lugs 25 of collars 18 to position indicated by full lines in Fig. 10, and in which positions, said lugs permit operation or setting of the 60 respective actuators.

It is sometimes desirable and necessary to connect a multiplicity of columns to represent a political party; and this arrangement for primary elections, requires coupling together 65 of the rock shafts 31 of the several

columns, so that when one of the said rock shafts is moved, all three will be simultaneously moved. This can be accomplished in a very simple manner by the use of one or more links 66 (see Figs. 5 and 5^a), the ends 70 of which are perforated and are adapted to be mounted pivotally on the pins 37^c of the heads 37.

In Fig. 1, the main frame of the machine is indicated, as an entirety, by the numeral 75 67 and the numeral 68 indicates folding wings adapted to constitute parts of the voting booths when opened up and adapted to cover up the keyboard mechanism when folded or closed. Also, Fig. 1 illustrates 80 a multiplex voting machine of the general character disclosed and claimed broadly in my prior patent above identified.

What I claim is:

1. In a voting machine, the combination 85 with several groups of register actuators, of actuator locks for the several groups of actuators, key-actuated means for operating said actuator locks, and a common lock operated by the first key-actuated actuator-lock, to 90 lock all other actuator locks against movement.

2. In a voting machine, the combination 95 with a multiplicity of groups of register actuators, of a lock bar for each group of actuators normally locking the same, key-actuated means for moving said lock bars into releasing positions, and means whereby movement of one of said lock bars will lock all of the other lock bars in their normal 100 actuator-locking positions.

3. In a voting machine, the combination 105 with a plurality of groups of register actuators, of lock bars for each group of actuators normally locking the same, key-actuated means for independently releasing said lock bars, a common lock bar for the said several actuator-lock bars normally permitting movement of one of the said actuator lock bars but arranged to be set by the movement 110 of the first thereof, to lock all other actuator-locking bars in their normal actuator-locking positions.

4. In a voting machine, the combination 115 with several groups of register actuators, of actuator locks for the several groups of actuators, key-actuated means for operating said actuator locks, a common lock operated by the first key-actuated actuator-lock, to lock 120 all other actuator locks against movement, and a lock-controlled cut-off strip movable to and from a position in which it will cut off access to key-actuated means.

5. In a voting machine, the combination 125 with several groups of register actuators, of actuator-locks for the several groups of actuators, key-actuated means for operating said actuator-locks, a common lock operated by the first key-actuated actuator-lock to lock all of the other actuators locked against 130

movement, a voter's crank and connections whereby movement of the latter will restore set actuators to normal position and will also restore to normal position the said actuator-locks and the common lock therefor.

6. In a voting machine, the combination with several groups of register actuators, of actuator locks for the several groups of actuators, key-actuated means for operating said actuator locks, and a common lock coöp-

eratively associated with the mechanism noted and set for action in respect to the first actuator lock.

In testimony whereof I affix my signature in presence of two witnesses.

SYVER LOE.
